UNITED STATES PATENT OFFICE.

CHARLES D. BLAIKIE, OF ATTLEBORO, MASSACHUSETTS.

WIRE FABRIC.

Application filed January 28, 1924. Serial No. 689,142.

To all whom it may concern:

Be it known that I, CHARLES D. BLAIKIE, a citizen of the United States, residing at 4 East Street, Attleboro, of the county of Bristol and State of Massachusetts, have invented certain new and useful Improvements in Wire Fabrics, of which the following is a specification.

My invention relates to improvements in wire fabrics adapted for use on bracelets, mesh-bag handles, etc., and to this end comprises a new article of manufacture having a seamless woven wire tubular covering and a flexible cylindrical core.

I am aware that it is old to construct seamless tubes composed of a plurality of longitudinally extending helical wires inter-linked with each other. Fabrics of this nature are quite extensively manufactured, and are commonly called "woven wire" in the trade, though having no filling or woof strands are not strictly speaking woven. Seamless tubes constructed of this material are generally more attractive in appearance, more elastic and have greater durability than real woven wire or other types of wire seamless tubes. I take a seamless tube of this construction and insert therein a flexible, circular, stiffening core, and produce as a new article of manufacture a fabric of pleasing design, yet strong and readily flexible in all directions, adapted among a large variety of uses especially for use on bracelets and handles for chain-mesh bags, where strength and flexibility are desired. One object of my invention is thus to provide an article constructed from woven wire of more pleasing appearance than hitherto.

A further object of my invention is to provide an article constructed of woven wire of greater flexibility than hitherto, rendering articles constructed from seamless tubes thereof really practical for use on mesh-bag handles, where general flexibility and inherent strength are required.

A further object of my invention is to provide an article constructed from woven wire having greater inherent strength than hitherto, thereby greatly enlarging the field of use of seamless woven wire tubes.

A further object of my invention is to provide an article of this type, which when once bent to the desired configuration, will inherently always tend to resume that configuration after distortion in use.

These and such other objects of my invention as may hereinafter appear will be best understood from a description of the embodiments thereof shown in the accompanying drawings.

In the drawings, Fig. 1 is a side elevation of my invention.

Fig. 2 is an enlarged side elevation of my invention.

Fig. 3 is an enlarged cross-sectional view of the same, taken along the line 3—3 in Fig. 2.

Fig. 4 is an enlarged longitudinal sectional view of the same.

Fig. 5 is an enlarged side elevation of two strands of the longitudinally extending interlinked helical wires.

Fig. 6 is an enlarged detail view of the seamless tubular covering.

Fig. 7 is an enlarged perspective view of the closely wound helical spring core.

Fig. 8 is an enlarged perspective view of the flat inner spring.

Fig. 9 is a perspective view of a bracelet constructed of my invention.

Figure 10 is a cross-sectional view of a modified form of my invention.

Fig. 11 is a longitudinal sectional view of the modified form of my invention.

Fig. 12 is a perspective view of the flexible metallic strengthening core of the modified form of my invention shown in Figs. 10 and 11.

In the drawings wherein like characters of reference indicate like parts throughout, generally indicates my complete invention. Fig. 6 indicates the seamless tubular covering 16 made up of a plurality of the longitudinally extending interlinked helical wires 18, two strands of which are shown in detail in Fig. 5 interlinked in the usual manner.

The seamless tube 16 of longitudinally extending helical wires 18 inter-linked with each other is made in the usual manner as indicated in Patent No. 788,221 to H. B. Richardson, April 25, 1905. Said tube 16 may be placed on a stretching arbor,

and the flexible strengthening cylindrical core 17 inserted therein as the tubular covering 16 is drawn off the stretching arbor.

This insures a tight flush fit between the seamless tubular covering 16 and the flexible strengthening core 17. The core 17 comprises in the preferred embodiment shown in Figs. 2 to 4 and 6 to 8 the closely

wound helical flexible stiffening spring 20 (Fig. 7) which may be inserted within the tubular seamless covering 16 as it is drawn off the stretching arbor, and the flat stiffening spring 21 contained therein. The spring 21 may then be inserted within the spring 20. Though the closely wound helical, flexible, stiffening spring 20 is preferably of circular cross-section, it may be made of any shape without departing from my invention.

The helical spring 20 serves to give the circular sectional formation to the completed article, whereas the flat spring 21 being stiffer serves, when the article is made into a bracelet as in Fig. 9 or a mesh-bag handle, to resiliently spring the article back to the desired former shape after distortion in use. We thus see that each member functions in the combination completed article. The seamless tubular covering 16 made up of a plurality of longitudinally extending interlinked helical wires 18 serves to give strength and a pleasing appearance with a slight amount of resiliency to the completed article. The closely wound helical spring 20 serves to make the completed article cylindrical, aids its resiliency, and strengthens it. The flat spring 21 serves when once bent to the desired configuration to make the article capable of resiliently springing back to the desired configuration after distortion in use, and gives additional stiffening effect.

Fig. 9 shows a bracelet 25 constructed of the material of my invention. It is obvious how necessary it is for a bracelet to resume its original shape after having been put on or taken off.

In Figs. 10 to 12, I show a modified form of my invention wherein the flexible strengthening core 17 is approximately solid. As shown, this comprises a strip of fabricated wire, woven or otherwise, rolled over to form a solid flexible tubular core 30 having the seam 31 therein. It is obvious, however, that any flexible strengthening material, preferably of cylindrical shape, metallic or otherwise, may be employed as the core 17 without in any way departing from my invention. It is also obvious that suitable equivalents may be substituted for the cylindrical helical spring 20, such as the fabricated wire core shown in Figs. 10 to 12, and that if desired the flat strengthening spring 21 or its equivalent may be inserted in the embodiment shown in Figs. 10 to 12. If desired equivalents may be substituted as means to give the article greater stiffness and resiliency for the flat stiffening spring 21 shown. It is obvious that I have provided a wire fabric of improved construction of more pleasing appearance, of greater strength, flexibility, and resiliency than hitherto, wherein each part co-operates to add functions to the completed article.

I employ the word "woven" wire to comprise a wire fabric composed of a series of wire helices interlinked with each other, whether the helices extend longitudinally of the fabric and are transversely interlinked with each other as in my preferred embodiment, or whether they extend circumferentially of the fabric and are longitudinally interlinked with each other.

It is understood that my invention is not limited to the specific embodiments shown and that various deviations may be made therefrom without departing from the spirit and scope of the appended claims.

What I claim as new and desire to secure by Letters Patent is:

1. An article of jewelry composed of a seamless woven wire tubular covering made up of a plurality of wire helices interlinked with each other and a flexible strengthening cylindrical metallic core.

2. An article of jewelry composed of a seamless woven wire tubular covering made up of a plurality of longitudinally extending helical wires transversely interlinked with each other and a flexible strengthening cylindrical metallic core.

3. An article of jewelry composed of a seamless tubular covering made up of a plurality of longitudinally extending helical wires transversely interlinked with each other, and a closely wound helical flexible stiffening spring contained therein.

4. An article of jewelry composed of a seamless woven wire tubular covering made up of a plurality of wire helices interlinked with each other and a closely wound helical flexible stiffening spring contained therein.

5. An article of manufacture composed of a seamless tubular covering made up of a plurality of longitudinally extending helical wires transversely interlinked with each other, a closely wound helical flexible stiffening spring contained therein, and a flat stiffening spring contained in said helical spring.

6. An article of manufacture composed of a seamless tubular covering made up of a plurality of longitudinally extending helical wires transversely interlinked with each other, a closely wound helical flexible stiffening spring tightly contained therein, and a flat stiffening spring contained in said helical spring.

7. An article of manufacture composed of a seamless tubular covering made up of a plurality of wire helices interlinked with each other, a closely wound helical flexible stiffening spring contained therein, and a flat stiffening spring contained in said helical spring.

8. An article of manufacture composed of a seamless tubular covering made up of a plurality of wire helices interlinked with each other, a closely wound helical flexible

stiffening spring tightly contained therein, and a flat stiffening spring contained in said helical spring.

9. An article of manufacture composed of a seamless tubular covering made up of a plurality of longitudinally extending helical wires transversely interlinked with each other, a flexible strengthening cylindrical core contained therein, and stiffening means contained within said core.

10. An article of manufacture composed of a seamless tubular covering made up of a plurality of longitudinally extending helical wires transversely interlinked with each other, a flexible strengthening core contained therein, and stiffening means contained within said core.

11. An article of manufacture composed of a seamless woven wire tubular covering made up of a plurality of wire helices interlinked with each other, a flexible strengthening cylindrical core contained therein, and stiffening means contained within said core.

12. An article of manufacture composed of a seamless woven wire tubular covering made up of a plurality of wire helices interlinked with each other, a flexible strengthening core contained therein, and stiffening means contained within said core.

13. An article of manufacture composed of a seamless tubular covering made up of a plurality of longitudinally extending helical wires transversely interlinked with each other, a flexible strengthening core contained therein, and a flat stiffening spring contained within said core.

14. An article of manufacture composed of a seamless woven wire tubular covering made up of a plurality of wire helices interlinked with each other, a flexible strengthening core contained therein, and a flat stiffening spring contained within said core.

In testimony whereof I affix my signature.

CHARLES D. BLAIKIE.
